DESCRIPTION

FIG. 1 is a perspective view of an electric hair dryer of the present invention showing my new design;

FIG. 2 is a front elevational view of the electric hair dryer of FIG. 1;

FIG. 3 is a left side elevational view of the electric hair dryer of FIG. 1, the right side elevational view being a mirror image thereof;

FIG. 4 is a top plan view of the electric hair dryer of FIG. 1; and,

FIG. 5 is a bottom plan view of the electric hair dryer of FIG. 1.

Subject matter shown in broken lines represents environment and does not form a part of the claimed design. The rear elevational view forms no part of the claimed design.
